UNITED STATES PATENT OFFICE.

ZOEL PERRAULT, OF REEDS FERRY, NEW HAMPSHIRE.

SHADE-HANGER.

1,153,949.

Specification of Letters Patent. Patented Sept. 21, 1915.

Application filed May 9, 1914. Serial No. 837,491.

To all whom it may concern:

Be it known that I, ZOEL PERRAULT, a citizen of the United States, residing at Reeds Ferry, in the county of Hillsboro and 5 State of New Hampshire, have invented certain new and useful Improvements in Shade-Hangers, of which the following is a specification.

This invention relates to shade hangers 10 and has primarily for its object to provide a device capable of adjustment so as to be adaptable for use on window casings of various sizes.

Another object is to provide a novel form 15 of locking means by which the device is held positively in engagement with the window casing minus the use of nails, screws, etc.

Other objects as well as the nature, characteristic features and scope of my invention will be more readily understood from the following description taken in connection with the accompanying drawings and pointed out in the claim forming a part of 20 this specification.

Referring to the drawings: Figure 1 is a front elevation of a hanger constructed in accordance with my invention, illustrating the application thereof, Fig. 2 is a side elevation of the same, Fig. 3 is an enlarged fragmentary view of a detail, Fig. 4 is a sectional view taken on the line 4—4 of Fig. 1, and Fig. 5 is a bottom plan view of the movable jaw used in the present invention. 35 Fig. 6 is a detail view of the inner ends of the movable hanger members.

In the drawings, wherein is illustrated the preferred embodiment of this invention in order to illustrate the application thereof, 40 a support 5 is provided which in the present instance represents a window casing with which my improved shade hanging device, generally designated 6, is associated. The hanger 6, in the present instance, comprises 45 a pair of relatively movable members 7, each of which has formed in one end thereof an elongated slot 8, through one of which a screw 9 is passed for detachably engaging the proximate ends of the members 7, said members provided with tapered intermediate portions 10, so as to provide shoulders 11 for a purpose which will subsequently appear. The outer terminal of one of the members 7 is turned in right-angled relation to the body, so as to provide a jaw 12 55 for engagement with one of the marginal

edges of the window casing 5, the jaw being provided with teeth so as to bite into the casing thereby positively engaging the same therewith and preventing its accidental displacement. The opposite member 7 is raised as indicated at 13 adjacent its outer terminal, said raised portion being provided with an elongated slot 14 in which is slidably mounted a stud 15 which is carried by 60 the movable jaw 16, the latter provided with an elongated slot 17 in which engages a tongue 18, said tongue being formed by reducing the extreme end of the last mentioned member 7, as shown to advantage in 65 Fig. 3. The movable jaw 16 is provided with teeth 19 which bite in the casing on the opposite marginal edge from that with which the jaw 12 is engaged. The inner end of one of the members 7 has a neck 7' extending therefrom and in right angled relation to the body, on which is formed a head 7², the neck 7' engaging through the slot 8 on the opposite member 7, while the head is engaged therewith, preventing transverse movement of the members 7, even in 75 the event that undue pressure is exerted thereon, since by mounting the screw 9 on the end of one of the members 7 and passing it through the slot 8 in the opposite member 7, the members 7 would be readily displaced by any undue pressure, as is the case in devices of this character now in use. 80

In order to engage the jaws 12 and 16 with the opposite side of the casing, a cam lever 20 is interposed between the raised portion 13 and the tongue 18 of the member 7, and is provided on its upper face with a pivot pin 21 which engages through the movable jaw 16 thereby imparting movement to the latter, when pressure is exerted on the cam lever 20, while the latter is limited in its movement by the provision of a tooth 22 which projects from the periphery of the cam and abuts one side of the 90 tongue 18, said lever 20 being provided with a finger-piece 23, so as to facilitate the actuation of the same.

The shade supporting members, as indicated at 24 are identical in configuration, 105 each comprising an elongated base, one end 25 of which is turned at right angles to the body for engagement with one end of the window shade, in the usual manner. A slot 26 is formed in each of the members 24, 110 while the inner end of each of the latter is provided with laterally projecting ears 27

which engage with the reduced portions 10 of the members 7, thereby permitting the shade supporting member 24 to slide on the members 7 and independently thereof, being held in predetermined positions through the medium of set-screws 28, said members 7 being provided with openings 29 through which the screws 28 engage.

In operation, the members 7 are first adapted so as to snugly engage with the opposite marginal edges of the window casing, and the cam lever 20, then actuated so that the teeth on the jaws 12 and 16 will bite into the casing, thereby positively preventing the accidental displacement of the same. The shade supporting members, 24 are then adapted so as to conform to the length of the shade and are engaged therewith in the usual manner, after which the screws 28 are tightened preventing the accidental displacement of the window shade. When desired, the device may be expeditiously removed from the window casing by merely disengaging the jaws 12 and 16 therefrom which is accomplished by releasing the cam-lever 20.

It will be understood that the above description and accompanying drawings com-

prehend only the general and preferred embodiment of my invention and that various minor changes in details of construction, proportion and arrangement of parts, may be made within the scope of the appended claim and without sacrificing any of the advantages of my invention.

Having thus fully described my invention what I claim as new and desire to secure by Letters Patent is:

A shade hanger including a pair of slidably connected relatively movable casing engaging members, each of which is reduced to provide shoulders, shade supporting brackets slidably mounted on the reduced portions of said members and having tongues extending therefrom for abutment with said shoulders for limiting the movement of said brackets in one direction, and means for engaging said members with the window casing.

In testimony whereof I have affixed my signature in presence of two witnesses.

ZOEL PERRAULT.
